UNITED STATES PATENT OFFICE.

LEE PERKINS BIGGERS, OF PALMERSVILLE, TENNESSEE, ASSIGNOR OF SIXTEEN PER CENT TO HOMER BUCKLEY, OF MARTIN, TENNESSEE, SIXTEEN PER CENT TO BLAINE BIGGERS, OF ST. LOUIS, MISSOURI, AND SIXTEEN PER CENT TO EDWARD McAULIFF, OF EAST ST. LOUIS, ILLINOIS.

PLOW.

Application filed November 4, 1922. Serial No. 599,108.

To all whom it may concern:

Be it known that I, LEE P. BIGGERS, a citizen of the United States, residing at Palmersville, in the county of Weakley and State of Tennessee, have invented a new and useful Improvement in Plows, of which the following is a specification.

My invention relates to a plow of the rotary type which may also be used as a pulverizer by an interchange of the earth-working elements or tools, or by employing elements or tools of both types, may be used both to plow and harrow simultaneously.

One of the important features of the invention relates to the manner in which the earth-working elements are disposed, whereby the rotation of the same, in addition to working the earth, furnishes either a part or all of the force by which the implement may be propelled over the surface of the ground.

A further object of the invention is to so construct the implement that the various parts thereof may be easily assembled or disassembled for the purpose of replacing worn or broken parts, or for sharpening the earth-working elements.

The invention consists further in the arrangement of the shafts on which the earth-working elements are mounted so that they extend in the direction of the line of draft, and also in the arrangement of the earth-working elements on the shaft, so that part of them are engaged with the ground while others are in the air, and the elements on either side of the machine are so balanced that there will be little tendency to move sidewise.

The invention will be better understood by the following description, taken in connection with the accompanying drawings, which illustrate one structure by means of which the invention may be carried out.

In the drawings:

Fig. 1 is a plan view of the invention.

Fig. 2 is a horizontal sectional view.

Fig. 3 is a rear elevation.

Fig. 4 is a side elevation.

Fig. 5 is a plan view of a portion of the invention showing a modified construction.

Fig. 6 is a detail sectional view showing the means for mounting the plow shafts.

Figs. 7 and 8 are detail views of different types of earth-working elements.

Referring now to the details of construction. The invention comprises a rectangular frame having front and rear members 1 and 2, respectively, connected by side members 3 and 4, each of which is provided with a flange 5 at each end secured to the members 1 and 2 by bolts 6 or the like. The frame members 1 and 2 are each made hollow and provided along the inner edge with slots 7 and 8, respectively, through which the shafts that carry the earth-working elements extend. The member 1 may also be provided on its forward side with a slot 9 in order that the shafts may, if desired extend therethrough and be driven from gearing on the front side of the frame, as will be more fully explained hereinafter.

A series of blocks 10 are fitted within the frame members 1 and 2, and are adjustable longitudinally therein, these blocks serving as journal bearings for the shafts 11. Between these blocks 10 are arranged alternately the complementary spacing blocks 12, which may also be provided with bearings 13 for receiving additional shafts, or in order to provide further latitude in the relative arrangements of the shafts. The blocks 10 and 12 are secured at the ends of the members 1 and 2 by end blocks 14, which may be adjusted by means of screws 15 or the like.

The shafts 11 are preferably provided at their forward ends with ball races 16 which take up the forward thrust exerted by the earth-working elements 17 or 18 carried by the shafts.

It will be noted that the earth-working elements are disposed in planes which are inclined to the direction of the shafts on which they are mounted, so that as the elements engage the ground, they will exert a forward thrust against the frame of the implement after the manner of a ship propeller. The elements 17 have the same function as ordinary disk plows, but, as shown, are preferably made in the shape of sectors and so disposed in relation to the circumference of the shafts that certain of the disks engage the ground while others are in the air, thus distributing the load so as to obtain a continuous and substantially uniform action

and thereby make it possible to operate the plow with less power than would otherwise be necessary.

- In order that the disks 17 may be removed with the least possible trouble, when it is necessary for them to be sharpened, each disk is preferably provided with a slotted hub, as shown at 19, whereby the same may be applied to the shaft and secured thereon by means of clamping members 20 and 21, fastened together by means of bolts 22. Clamping screws 23 may also be provided to secure the clamps against longitudinal movement on the shaft. The opposed faces of the members 20 and 21 are preferably disposed at a slight inclination with respect to the axis of the shaft 11, in order to furnish the propelling force. In actual practice, the preferred angle has been found to be about 12 degrees from a perpendicular, but this may be varied according to the speed of revolution and the width of cut desired. The pulverizing elements 18 are formed each with a hub 24 adapted to receive the shaft, and a cap 25 which is secured thereto by means of bolts 26.

The shafts 11 may be driven in any suitable manner. In Figs. 1 to 4, I have shown each shaft provided with a sprocket wheel 27, which is connected, by a sprocket chain 28, to the drive shaft 29, that is mounted in bearings at the upper ends of the standards 30 and 31, rising from the main frame of the machine and from the motor support 32, respectively. The shaft 29 is driven through bevel gearing 33 or the like from the motor 34 which, as will be understood, may be provided with the usual clutch and gear shift.

In Fig. 5, I have shown a modified driving gear in which the shafts 11 are extended, as at 35, through the slot 9 at the forward side of the frame member 1, and provided at their forward ends with a bevel gear connection 36 with a countershaft 37 journaled in bearings 38 at the forward side of the frame. This countershaft 37 may be provided with a sprocket wheel 39, that may be connected with the motor shaft, by the usual sprocket chain.

The frame of the machine is supported at the rear, the proper distance above the ground, by means of wheels 40, each of which is carried by a fork member 41, the latter being adjustably connected by means of corrugations or teeth 42 with an upstanding bracket 43, secured to the side of the frame. The members 41 and 43 are secured in their adjusted relation by means of a bolt 44 which extends through the member 41 and through a slot 45 in the bracket 43.

The front or steering wheel 46 is secured at the lower end of a fork member 47, which is rotatably mounted in a bearing 48, and held against longitudinal movement by a

collar 49. The fork member 47 is provided at its upper end with a tiller arm 50. The bearing member 48 is formed in a bracket 52, adjustably connected with a standard 51, in a manner similar to the rear wheel forks. 70

It is understood that the plow disks 17 will be set at such an inclination to the shafts 11 that, ordinarily, the machine will be propelled over the ground by the forward thrust exerted by the disks upon rotation, 75 and that the disks will, at the same time, plow the earth. In order, however, to use the machine under all conditions and in all kinds of ground, it may, in some instances, be necessary to employ one or more draft animals or a tractor to supplement the propelling force of the plows. In such cases, however, only a small additional force will need to be exerted by the draft animals.

As illustrated in Figs. 1 and 2, each of 85 the shafts 11 may be provided with both a plow disk 17 and a pulverizing tooth 18, so that one trip across the ground will both plow and harrow it.

The essential features of the invention 90 may also, with slight modifications in the frame, be used in road grading. It will also be observed that an implement constructed according to my invention may be completely disassembled in the least possible time by removing the screws 15 and bolts 6 at one side of the frame.

While I have shown and described the specific construction of those forms of my invention which are at present preferred, it 10 will be observed that various modifications may be made therein within the scope of what is claimed without departing from the spirit of the invention.

What is claimed is:—

1. In a wheeled plow, a plurality of parallel shafts disposed substantially in the line of travel, sector-shaped disk plows rigidly mounted on the shafts in planes oblique to the axes of the respective shafts, a pulverizing tooth on each shaft also inclined to the direction of the shaft, and a motor to which the shafts are geared to rotate in unison, said shafts being so disposed that certain of the disk sectors on each side of the implement will engage the ground simultaneously while others on each side are above the ground, whereby the load is distributed so as to obtain a continuous and substantially uniform action. 11

2. In an earth working machine, a rectangular frame having two side members connected by hollow front and rear members, a series of bearing blocks slidably mounted in end to end relation within each of the hollow members, means engageable with the end blocks to adjust all of said blocks simultaneously as a unit longitudinally of the hollow member, the opposed faces of said hollow members being longi- 12

- tudinally slotted, shafts having their ends extending through said slots and journaled in said blocks, earth working elements mounted on said shafts, and means for rotating the shafts.
3. In an earth working machine, a rectangular frame having two side members connected by hollow front and rear members, the opposed faces of which are longitudinally slotted, a series of bearing blocks mounted within said hollow members and held by the walls thereof against lateral movement, adjustable means bearing against the end blocks for retaining all of said blocks against endwise movement, shafts having their ends extending through the slots and journaled in said blocks, earth working elements mounted on said shafts, and means for rotating the shafts.
4. In an earth working machine, a rectangular frame having hollow slotted front and rear members, a pair of side members removably secured thereto, a series of bearing blocks slidably adjustable within the front and rear members and removable only from the ends thereof when the side members are removed, a plurality of shafts having their ends extending through the slots and journaled in said blocks, earth-working elements mounted on the shaft, and a motor in driving relation to the shafts.
5. In an earth working machine, a rectangular frame having longitudinal side members, hollow front and rear members having opposed slots extending longitudinally thereof, a series of blocks slidably adjustable within the hollow members, a plurality of shafts extending through the slots and journaled in the blocks, the front hollow member having also a slot through the front side thereof, a countershaft journaled in front of the same, each of said plurality of shafts being extended through the last-named slot and geared to the countershaft, and a motor geared to the countershaft.
6. In an earth working machine, a rectangular frame having longitudinal side members, hollow front and rear members removably secured thereto and having opposed slots, a series of bearing blocks slidably adjustable within the hollow members, spacing blocks arranged alternately with the bearing blocks, set screws in the side members engageable with the ends of each series of blocks to clamp them in position, earth-working elements mounted on said shafts, a slot through the front side of the front hollow member, a countershaft journaled in front of the same, each of said plurality of shafts being extended through the last-named slot and geared to the countershaft, and a motor in driving relation to the countershaft.
7. In a wheeled plow, a rectangular frame having longitudinal side members, hollow front and rear members removably secured thereto and having opposed slots, a series of bearing blocks slidably adjustable within the hollow members, spacing blocks arranged alternately with the bearing blocks, set screws in the side members engageable with the ends of each series of blocks to clamp them in position, a plurality of shafts extending through the slots and journaled in the blocks, earth-working elements mounted on said shafts, and a motor connected with all of said shafts to drive them in unison.

In testimony, that I claim the foregoing as my own, I have hereto affixed my signature.

LEE PERKINS BIGGERS.
